Des. 238,978
Patented Feb. 24, 1976

238,978

THERMODYNAMIC CONTAINER AND THE LIKE

Ira E. Getchell, Jr., 195 Evergreen Parkway, Oceanside,
Calif. 92054, and Thomas D. Peat, 435 N. Myrtle
Ave., Monrovia, Calif. 91016

Filed Aug. 12, 1974, Ser. No. 496,377

Term of patent 14 years

Int. Cl. D3—02

U.S. Cl. D87—1 R

Fig. 1

Fig. 2

Fig. 3

Fig. 4

Fig. 5

FIG. 1 is a right front perspective view of a thermodynamic container or the like showing our new design;

FIG. 2 is a left side elevational view thereof, the opposite end being the same as the end shown;

FIG. 3 is a righthand elevational view thereof, the opposite end being the same as the end shown;

FIG. 4 is a top plan view thereof; and

FIG. 5 is a bottom plan view thereof.

We claim:

The ornamental design for a thermodynamic container and the like, as shown and described.
